UNITED STATES PATENT OFFICE.

HARRISON S. MILLER, OF INDIANAPOLIS, INDIANA, ASSIGNOR OF ONE-HALF
TO WILLIAM H. MARTZ, OF SAME PLACE.

WATER-GOVERNOR.

SPECIFICATION forming part of Letters Patent No. 257,509, dated May 9, 1882.

Application filed July 16, 1880. (No model.)

To all whom it may concern:

Be it known that I, HARRISON S. MILLER, of the city of Indianapolis, county of Marion, and State of Indiana, have invented certain new 5 and useful Improvements in Water-Governors, of which the following is a specification.

The object of my invention is to produce a perfectly-balanced water-governor which will act under all circumstances with certainty and 10 celerity. This is accomplished by passing the valve through the bottom of the receiving-chamber into a separate chamber below and connecting such lower chamber with the discharging-chamber on the opposite side of the receiving-chamber therefrom by means of a tubular connection through the valve and valve-stem.

Referring to the accompanying drawings, which are made a part hereof, Figure 1 is a side elevation of a water-governor embodying 20 my improvements, and Fig. 2 is a vertical section through the center of the same.

In said drawings, the portion marked A represents the casing or cylinder of my improved governor; B, a valve-seat, preferably cast in one 25 piece with said casing, which divides said casing into two chambers, C and D; C, a receiving-chamber, into which the water enters through the pipe C'; D, a second chamber, from which the water is discharged through the pipe D'; 30 E, a valve of peculiar construction, which is arranged to close the orifice b in the valve-seat B, and thus cut off communication between the two chambers when the water-pressure becomes great enough to cause the governor to 35 act; F, the valve-stem connecting the valve with the plunger; G, a plunger, made watertight with the cylinder, by means of which the water-pressure is enabled to operate the valve; H, the stem to said plunger, connecting it with 40 the lever I; J, a weight which is adjustably mounted on the hinged lever I, and by which the amount of pressure necessary to operate the governor is determined; and K, a third chamber below the chamber C, into which the lower 45 end of the valve E extends, and which connects through the small tubular openings e f with the upper or discharging chamber, D.

The operation of my governor is as follows: The water enters through the pipe C' into the

chamber C, from which it passes through the 50 orifice b in the valve-seat B into the chamber D. When the water-pressure in the chamber D exceeds the force exerted by the weight J the plunger G is forced up, carrying with it the valve E, thus closing the orifice b and preventing 55 the ingress of any more water into the chamber D. Whenever water is drawn off through the pipe D' or its connections the pressure in the chamber D is of course reduced, and the valve is forced back by the action of 60 the weight J, so as to admit more water.

If the valve E were constructed in the ordinary way, the pressure of the water upon the under side thereof in the chamber C would prevent it from falling back at the proper time. 65 I have therefore constructed the valve of an equal size throughout and extended it through a stuffing-box, a, in the lower end of the cylinder, so that its lower end shall not be affected by the pressure of the water in the chamber C, 70 which obviates such disadvantage. To still more perfectly secure the result last mentioned I cause an equal pressure to come upon the two ends of the valve when the same is closed by forming a chamber, K, around the lower end of 75 the valve, below the stuffing-box a. Said chamber is formed by chambering the nut or projection L that sets up the packing around the valve and I connect the chamber K with the chamber D by means of a tubular opening, e f, through 80 the valve itself and its valve-stem. By this means a perfectly equal pressure is maintained on all the corresponding parts of the valve, and the governor is therefore enabled to respond to the slightest variation in the pressure of the 85 water, and the pipes in the building connecting with the discharging-pipe D' are therefore always guarded against the danger of overstraining, notwithstanding any increase in the outside pressure.

The nut L has a double function. The said third chamber, in connection with the tube e and f, acts as a cushion or governor to the plunger, preventing jerking or violent movement of the plunger and valves when water is withdrawn, let in, or cut off. The said nut L is also used to set up the packing around the plunger or valve between the chambers K and C.

I do not claim broadly the device shown in the reissue patent of Bartholomew, May 15, 1866, No. 2,241.

Having thus fully described my said invention, what I claim as new, and desire to secure by Letters Patent, is—

In a water-governor, the combination of the two chambers C D, divided by the partition B, which also forms the valve-seat, and connected 10 by the opening b through said partition, the weighted stem H F, the plunger G, chamber-nut I, stuffing-box α , and valve E, the latter being of equal size throughout and extending

through into the third chamber, K, and provided with the orifice e f, leading from said 15 third chamber through into the upper or discharging chamber, D, all constructed, arranged, and operated substantially as shown and described, and for the purpose specified.

In witness whereof I have hereunto set my 20 hand and seal, at Indianapolis, Indiana, this 12th day of July, A. D. 1880.

HARRISON S. MILLER. [L. S.]

In presence of—

— C. BRADFORD,
ARTHUR HOLLADAY.
